US0D1029272S

(12) **United States Design Patent** (10) Patent No.: **US D1,029,272 S**
(45) Date of Patent: ** May 28, 2024

(54) **ROBOT ARM FOR INTERVENTIONAL SURGERY**

(71) Applicant: **Wuhan United Imaging Healthcare Surgical Technology Co., Ltd.**, Wuhan (CN)

(72) Inventor: **Shihui Liao**, Hubei (CN)

(**) Term: **15 Years**

(21) Appl. No.: **35/516,382**

(22) Filed: **Nov. 24, 2022**

(80) **Hague Agreement Data**

Int. Filing Date: **Nov. 24, 2022**

Int. Reg. No.: **DM/226659**

Int. Reg. Date: **Nov. 24, 2022**

Int. Reg. Pub. Date: **Feb. 24, 2023**

(30) **Foreign Application Priority Data**

May 24, 2022 (CN) 202230308084.0

(51) **LOC (14) Cl.** **24-02**

(52) **U.S. Cl.**

USPC **D24/185**

(57) **CLAIM**

The ornamental design for a robot arm for interventional surgery, as shown and described.

DESCRIPTION

The patent or application file contains at least one drawing executed in color. Copies of this patent or patent application publication with color drawing(s) will be provided by the Office upon request and payment of the necessary fee.

1. Robot arm for interventional surgery
